MAGAZINE GUN WITH MANUAL RELOADING MECHANISM

Frank T. Green and Wilfred I. Smith, Haydenville, Mass., assignors to Noble Manufacturing Co. Inc., Haydenville, Mass., a corporation of Massachusetts

Application June 28, 1957, Serial No. 668,719

1 Claim. (Cl. 42-17)

This invention relates to a magazine type gun having 15 manually-operated reloading mechanism.

It is the general object of the present invention to improve and simplify the reloading mechanism, to provide additional safety devices and to make the reloading operation exceptionally certain and reliable.

An important feature of the invention relates to an additional safety device which prevents repeated operation of the gun without interposed release of the trigger. We also provide an improved frame and casing for the magazine and reloading mechanism, an improved cartridge ejector, and an improved cartridge transfer device.

Our invention further relates to arrangements and combinations of parts which will be hereinafter described and more particularly pointed out in the appended claims.

A preferred form of the invention is shown in the drawings, in which

Fig. 1 is a right side elevation of the magazine frame and housing, with the right side plate removed and with the breechbolt locked in firing position;

Fig. 2 is a view similar to Fig. 1 but with the breech-bolt in extreme left-hand position for ejecting a used cartridge;

Fig. 3 is a sectional end elevation, looking in the direction of the arrow 3 in Fig. 2;

Fig. 4 is a view similar to Fig. 2 but showing the breechbolt partially advanced and with a new cartridge in raised position;

Fig. 5 is a right side elevation of the left casing plate, together with certain parts carried thereby;

Figs. 6, 6a, 7 and 8 are sectional elevations, taken along the lines 6—6, 6a—6a, 7—7 and 8—8 in Fig. 5 and particularly showing the pump bar construction;

Fig. 9 is a perspective view of the main frame in which the reloading and firing mechanism is assembled;

Fig. 10 is a right side view of the right casing plate;

Fig. 10a is a sectional view, taken along the line 10a—10a in Fig. 10;

Fig. 11 is a plan view of an auxiliary safety lever and spring, looking in the direction of the arrow 11 in Fig. 5;

Fig. 12 is a view of a cartridge retainer rocker arm, looking in the direction of the arrow 12 in Fig. 5;

Fig. 13 is a right side view of the trigger and hammer assembly, partly in section and with the hammer released;

Fig. 14 is a left side elevation of the cartridge transfer lever and certain associated parts;

Fig. 15 is a plan view of the same parts, looking in the direction of the arrow 15 in Fig. 14;

Fig. 16 is a plan view of the breechbolt and ejector;

Fig. 17 is a right side elevation of the breechbolt, looking in the direction of the arrow 17 in Fig. 16;

Fig. 18 is a left side elevation of the breechbolt, looking in the direction of the arrow 18 in Fig. 16;

Fig. 19 is an end elevation of the bolt, looking in the direction of the arrow 19 in Fig. 16;

2

Fig. 20 is a left side elevation of an ejector to be described;

Fig. 21 is an end view, looking in the direction of the arrow 21 in Fig. 20;

Fig. 22 is an enlarged sectional right side elevation showing the hammer and sear assembly and with the hammer cocked;

Fig. 23 is a right side elevation of the trigger;

Fig. 24 is a plan view thereof, looking in the direction 10 of the arrow 24 in Fig. 23;

Fig. 25 is a sear release member;

Fig. 26 is a right side elevation of the sear;

Fig. 27 is an end view of the sear, looking in the direction of the arrow 27 in Fig. 26;

Fig. 28 is a right side elevation of the hammer;

Fig. 29 is an edge view, looking in the direction of the arrow 29 in Fig. 28;

Fig. 30 is a plan view of a trigger spring;

Fig. 30a is a side elevation thereof;

Fig. 31 is a plan view of a sear connector lever spring; and

Fig. 31a is a side elevation thereof.

Referring to the drawings, we have shown our invention embodied in a shotgun having a barrel 40 (Fig. 2)

25 fixed in the front end of a frame member 41 (Fig. 9) and having a magazine or storage tube 42 (Fig. 2) fixed in a downward projection 43 (Fig. 9) of the frame member 41. The frame member 41 also has a rearward end portion 44 which is firmly seated in the usual butt 45.

30 A right side plate 47 (Fig. 10) is firmly secured to the right side of the frame member 41 and a left side plate 48 (Fig. 5) is firmly secured to the left side thereof. A trigger frame unit 49 (Fig. 4) completes the frame assembly. The right side plate 47 (Fig. 10) has a lug 35 47a (Fig. 10a) on its left side face, for a purpose to be described.

35 A breechbolt 50 (Fig. 16) is mounted to slide in a rearwardly and downwardly inclined direction in the magazine enclosure formed by the frame member 41, 40 the right side plate 47 and the left side plate 48. The right side plate 47 is cut away at its upper right-hand portion as shown in Fig. 10 to provide clearance for ejection of the used cartridge shells.

The breechbolt 50 has the usual firing-pin 52 associated with an anvil 53 and having the usual firing-spring 54. A hole in the upper part of the end portion 44 (Fig. 9) provides clearance for the firing-pin anvil 53.

45 A yieldable shell-retaining spring 55 (Figs. 16 and 18) is mounted on the left side face of the breechbolt 50, and a pivoted hook lever or extractor 56 is mounted on the right side face of the bolt and is yieldingly pressed 50 inward by a small coil spring 57. There is a downward lug or projection 58 on the lower face of the bolt for a purpose to be described.

55 A shell ejector 60 (Figs. 20 and 21) is slidably mounted in the left side surface of the breechbolt and is retained in withdrawn or left-hand position by a small compression spring 61 (Fig. 16). When the bolt is moved to the extreme left for reloading the barrel, the ejector 60 strikes the end 44 of the frame member 41 and is moved relatively forward in the bolt to eject a used shell from the breechbolt.

60 A cartridge transfer member 70 (Fig. 4) is pivoted at 71 to the trigger frame member 49 and has a notch 72 in its lower left-hand surface portion which is engaged by the offset end of a wire spring 73 which holds the member 70 yieldingly in raised position when shifted upward.

The member 70 has an arm 75 (Fig. 4) pivoted at 76 at the left-hand end of the arm and held yieldingly in raised position and against a stop 77 by a spring 78. A second stop 47a (Figs. 10 and 10a) on the inside

of the right side cover plate 47 limits downward movement of the transfer lever.

The bolt 50 (Fig. 17) has notches 79 in its lower face which engage the upper corner of the arm 75 as the bolt is moved to the right in Fig. 4. This depresses the arm 75 and swings the transfer member 70 upward with a fresh cartridge as the bolt 50 is moved forward towards closed position. The forward movement of the cartridge is facilitated by the lug 58 under the breech-bolt 50.

After the arm 75 engages the stop 77 (Fig. 4), the bolt slides freely over the arm as it continues its travel to closed and locked position.

A hammer 80 (Fig. 22) is pivoted at 81 in the trigger frame unit 49 and has a shoulder 82 engaged by the free end of a sear 83 (Fig. 26) which is advanced to engaging position by a sear spring 83a (Fig. 22).

The sear is pivoted at 84 (Fig. 22) to the unit 49 and has an offset upward release arm 85 (Fig. 26). The upper end of the arm 85 is seated in a notch 87 (Fig. 25) in the upper face of a trigger link 88 normally raised by a spring 89 (Figs. 22, 31 and 31a).

The trigger 90 (Figs. 23 and 24) is pivoted at 91 in the trigger unit 49 and has a stud 92 (Fig. 24) which seats in a notch 93 (Fig. 25) in the top edge of the link 88. A trigger spring 94 is shown in Fig. 22 and in detail in Figs. 30 and 30a.

The hammer has a slot in one edge which is traversed by a pin 81a (Fig. 13) and on which is pivoted one end of a rod 81b. This rod extends freely through a hole in a fixed plate 81c. A spring 81d is mounted on the rod 81b, with one end of the spring abutting the plate 81c and the other engaging a shoulder on the rod 81b. The spring activates the hammer when the hammer is released from the sear 83.

An offset arm 95 (Fig. 23) on the trigger 90 is engaged by the lower end of a safety lock lever 96 (Fig. 4) when the safety slide 97 is moved manually rearward to locking position. The slide is selectively retained in either locking or unlocking position by a suitable spring (Fig. 4).

A pump-bar 100 is slideable in a guideway 101 (Fig. 5) in the left side plate 48 and has a lug 102 on its right side at the rear end thereof. It is partially recessed at 103 on its right side face and the recess extends to its forward end. The lug 102 on the pump-bar seats in an angular recess 104 (Fig. 18) in the left side face of the breechbolt 50 and effects operation of the bolt 50 by the pump-bar in the following manner:

The frame member 41 (Fig. 9) has a lower inner portion 41a with an inclined lower surface 41b and a right-hand beveled shoulder 41c.

When the pump-bar moves the breechbolt forward, the action of the lug 102 in the inclined slot 104 is such as to press the breechbolt upward against the surface 41b until the bolt passes the shoulder 41c, which forms a bolt locking area thereafter receiving the firing pressure. The lifting action is aided by the offset angular contour of the slot 104 (Fig. 18).

A cartridge retainer lever 105 (Fig. 5) is pivoted in a recess at 106 in the left side plate 48. This lever has an offset lug 107 at its forward end and an upwardly projecting cam lug 108 at the rearward end thereof. There is also a similar but reversed cam lug 109 at the forward end.

As the pump-bar 100 is moved to the rear, the rearward end of the bar 100 engages and depresses the cam lug 108 on the lever 105 and raises the opposite cam lug 109 into the pump-bar recess 103, as shown in Fig. 2. The offset lug 107 (Fig. 12) is thus brought up in front of the new cartridge and holds back the next cartridge in the magazine tube 42.

As the pump-bar is moved to the end of its forward stroke, the full-height rear end portion of the pump-bar engages and depresses the cam lug 109 and moves

the lug 107 below the path of the cartridge about to be placed on the transfer lever 70. The depending lug 58 on the under surface of the breechbolt then engages the new cartridge and pushes it into the gun barrel 40.

An auxiliary safety lever 110 (Figs. 5, 11 and 14) is pivoted at 111 on the trigger frame 49 and assumes the position shown in Fig. 5 when the hammer 80 is cocked. This lever 110 has a lateral locking lug 112 on its right side, an offset downward hand release 113 at its rear end, and an offset upward locking member 114 at its forward end.

A spring 115 is clamped by notches 116 (Fig. 5) on the lever 110 and forwardly of the pivot 111. This spring 115 crosses over the top of the lever 110 and the frame 49 and ends in a downward bent hook 117 (Fig. 5) which is engaged by a stud 118 (Fig. 22) on the hammer 80.

When the hammer is cocked, it turns the lever 110 counter-clockwise in Fig. 22 but when the hammer is released, it turns the lever clockwise. In the clockwise position, the forward locking member 114 on the lever 110 clears and releases the pump-bar 100, which can then be moved to the rear, i.e., to the left in Fig. 5, withdrawing the bolt 50 and extracting the used shell from the barrel.

When the hammer 80 is thus released, the pump-bar can be operated, but if the hammer 80 is cocked (Figs. 1 and 22), the pump-bar cannot be moved at all unless the release 113 of the lever 110 is manually pushed up against the pressure of the spring 115 which is then tensioned by the hammer stud 118.

The auxiliary safety lever 110 thus prevents accidental movement of the pump-bar 100 or of the bolt 50 while the hammer is cocked. Furthermore, the lug 112 of the lever 110 depresses the trigger link 88 (Figs. 13, 14 and 22) and thus prevents sear release of the trigger 90 until the rear end of the lever 110 is manually pushed up by release 113. This insures single-shot operation.

Should the trigger be held back while the pump-bar is operated, nothing will happen, as the trigger link 88 will not engage the sear until the trigger is released so that the trigger link notch 87 can again engage the release arm 85 of the sear 83.

Operation

In Fig. 1, the pump-bar is in full forward position, with the breechbolt in locked position, as by surface 41c ready to fire. The forward end of the cartridge retainer lever 105 has been moved to its lower position by the sliding movement of the pump-bar.

Fig. 5 shows the left side plate 48 with the pump-bar 100, the cartridge retainer lever 105 and the hammer safety lever 110 in their respective working positions when the gun is ready to fire. Fig. 5 also clearly shows the forward end 114 of the safety lever 110 blocking the pump-bar 100 from accidental backsiding or unlocking.

If the rearward end of the safety lever 110 is now pushed up manually, the pump-bar can be pushed to the rear to the extreme dotted position in Fig. 5. The rear end of the cartridge retainer lever 105 is thus pushed down by the pump-bar, which has a clearance 103 to receive the cam lug 109 at the forward end of the cartridge retainer lever 105.

The pump-bar thus rocks the cartridge retainer lever 105 in and out of position to act as a stop for the cartridges from the magazine, which cartridges can enter the loading area only at certain intervals in the cycle of loading and unloading.

If the breechbolt 50 is pushed back by the pump-bar 100 to its extreme rearward position, the back end of the ejector 60 will hit the back wall 44 of the frame 41 before the bolt does, and the front end of the ejector will thereby eject the cartridge with its beveled front edge which is shown in Fig. 21. This rearward motion of the bolt also cocks the hammer and brings the sear into position to hold the hammer cocked.

When the bolt is at the extreme rear position and the fired cartridge has been ejected, the shell stop spur 107 of the lever 105 is in the upper or retaining position. If now the pump-bar is pushed forward with the bolt hugging the inclined top under surface 41b of the receiver frame 41, the transfer lever 70 will be lifted at its forward end (Fig. 2) by means of the little notches at 79 of the bolt 50 retaining the edge of the small secondary lever or arm 75 mounted on the transfer lever. This causes the transfer lever to lift the new cartridge into position for the bolt to get behind it and shove it forward into the barrel. The bolt then slides over the end of the arm 75 and holds the transfer lever in raised position.

After the secondary lever or arm 75 of the transfer lever 70 has been left behind by the forward movement of the bolt, the depending lug 58 on the forward under surface of the bolt 50 will engage the concave upper forward surface of the transfer lever 70 and will return the lever to its lower position. The cartridge stop or lug 107 (Fig. 12) on the cartridge retainer lever 105 is moved downward by engagement with the full-height rear end portion of the pump-bar, and this allows a new cartridge to enter the loading area.

The lug 58 has the important additional function of stopping the next or entering shell after the cartridge retainer lever 105 has released the shell from the magazine tube. At this time, it is important that the next shell be prevented from moving completely back under the bolt, as this would prevent the gun being opened in the usual manner.

The lug 58 stops the shell, yet permits it to travel back with the bolt as the gun is opened, and to be ready to be lifted into position on the forward motion of the bolt.

A further forward movement of the pump-bar 100 will bring the bolt to the front edge of the main frame and into locking position. The safety lever 110 then snaps up behind the pump-bar to lock the same in place.

The usual safety catch prevents the trigger from releasing the hammer unless the catch is moved forward, which allows the trigger to push forward the link which swings the sear out of hammer-engagement, thereby allowing the hammer to give a sharp blow to the anvil on the firing pin and to cause the pin to indent the firing cap on the shell.

The hammer safety lever 110 which is pushed down by

the pump-bar, when ejecting and inserting a new cartridge, also pushes down the trigger link 88 and thereby directly prevents the release of the hammer by the sear during reloading.

Even should the trigger be held in a pulled-back position while the pump-rod is moved to press down on the automatic safety lever, the trigger link cannot engage the sear or release the hammer.

Having thus described our invention and the advantages thereof, we do not wish to be limited to the details herein disclosed, otherwise than as set forth in the claim, but what we claim is:

In a magazine gun, loading apparatus comprising an enclosing structure having a main frame, a separate and removable left side plate, a separate and removable right side plate and a trigger frame, and means to secure said frames and plates to each other to constitute a unitary structure which provides a substantially enclosed loading area, said enclosing structure supporting loading mechanism mounted in said structure and secured thereto, a movable breech-bolt in the enclosure, a locking surface for said breech-bolt in breech closed condition thereof, said locking surface being on the main frame and located in position to be exposed from side-to-side upon removal of the side plates from the main frame, said locking surface being substantially rectangular and extending directly across the main frame from side-to-side thereof.
